ROCKER-GLIDER SETTEE

Filed Jan. 7, 1948

Earl C. Allmand
INVENTOR.

ATTORNEY

UNITED STATES PATENT OFFICE

154,355

DESIGN FOR A ROCKER-GLIDER SETTEE

Earl C. Allmand, Dallas, Tex.

Application January 7, 1948, Serial No. 143,572

Term of patent 3½ years

(Cl. D15—1)

To all whom it may concern:

Be it known that I, Earl C. Allmand, a citizen of the United States, residing at Dallas, in the county of Dallas and State of Texas, have invented a new, original, and ornamental Design for Rocker-Glider Settee as shown, of which the following is a specification, reference being had to the accompanying drawing, forming part thereof:

Figure 1 is a front perspective view of a rocker-glider settee, showing my new design.

Figure 2 is a front elevational view, and

Figure 3 is an end elevational view thereof.

I claim:

The ornamental design for a rocker-glider settee, substantially as shown.

EARL C. ALLMAND.
